(57) **CLAIM**

The ornamental design for a display panel or portion thereof
with graphical user interface, as shown and described.

DESCRIPTION

The patent or application file contains at least one drawing
executed in color. Copies of this patent or patent application
publication with color drawing(s) will be provided by the
Office upon request and payment of the necessary fee.

FIG. 1 is a front view of a display panel or portion thereof
with graphical user interface showing our new design; and,
FIG. 2 is another front view thereof shown with the addition
of environmental subject matter.

The broken line forming a rectangle in FIG. 1, and the
innermost broken line rectangle shown in FIG. 2, illustrate
a display panel or portion thereof. The broken lines within
the rectangle thereof illustrate portions of the graphical user
interface. The remaining broken lines in FIG. 2 illustrate
environmental subject matter. None of the broken lines form
part of the claimed design. The white circle, and the area
therein, which appears within the broken line rectangle in
FIG. 1 and within the innermost broken line rectangle in
FIG. 2 form part of the claimed design.
